RELIGIOUS STATUETTE

John B. Garvey, Philadelphia, Pa.

Application June 9, 1954, Serial No. 30,892

Term of patent 7 years

(Cl. D29—23)

To all whom it may concern:

Be it known that I, John B. Garvey, a resident of the city of Philadelphia, in the county of Philadelphia, in the Commonwealth of Pennsylvania, have invented a new, original, and ornamental Design for a Religious Statuette, of which the following is a specification, reference being had to the accompanying drawing, forming a part hereof.

I claim:

The ornamental design for a religious statuette, substantially as shown.
